Primary Examiner — Cynthia R Underwood(57) **CLAIM**

The ornamental design for a silicone dinner plate, as shown and described.

DESCRIPTION

FIG. 1 is a top perspective view of a silicone dinner plate, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a cross-sectional view along a line labeled 8 in FIG. 6.

The broken lines are for environmental structure, boundaries, or illustrative purposes only and form no part of the claimed designs to be patented.

1 Claim, 8 Drawing Sheets(56)
